UNITED STATES PATENT OFFICE.

GEORGE G. J. MILLAR, OF GROVEPORT, OHIO, ASSIGNOR OF ONE-HALF TO
LUKE G. BYRNE, OF COLUMBUS, OHIO.

FOOT-PROPELLED VEHICLE.

SPECIFICATION forming part of Letters Patent No. 593,597, dated November 16, 1897.

Application filed February 3, 1896. Serial No. 577,869. (No model.)

To all whom it may concern:

Be it known that I, GEORGE G. J. MILLAR, a citizen of the United States, residing at Groveport, in the county of Franklin and State 5 of Ohio, have invented a new and useful Foot-Propelled Vehicle, of which the following is a specification.

This invention relates to an improvement in foot-propelled vehicles; and the object in 10 view is to simplify and improve the construction illustrated and described in former applications for patents, Serial No. 547,267, filed April 26, 1895, and Serial No. 561,982, filed September 9, 1895, both for improvement in 15 foot-propelled vehicles.

The primary object of the present invention is to produce a superior and advantageous construction of propelling mechanism, also to simplify and materially strengthen the frame 20 construction, and generally to make the several parts of the vehicle adjustable, whereby the comfort of the rider and passengers is added to.

One of the principal objects of the invention 25 is to make the vehicle convertible into either one of two forms of carriage—either a passenger-vehicle or a carrier such as is now largely used by stores, wholesale and retail, for the rapid delivery of small packages.

It is also the purpose of the present invention 30 to so arrange the passengers' seat and the operator's seat with relation to each other and the driving mechanism that space will be economized to the greatest possible extent and the machine as a whole thereby rendered more compact, much lighter and stronger, and as a result much neater and handsomer in appearance.

Other objects and advantages of the invention 35 will appear in the course of the ensuing description.

In the accompanying drawings, Figure 1 is a 40 perspective view of the improved vehicle adapted for carrying passengers and having the detachable canopy applied. Fig. 2 is a 45 side elevation, partly in section, showing the vehicle adapted for use as a carrier. Fig. 3 is a detail elevation showing the form of the crank-shaft and the manner in which it is 50 supported. Fig. 4 is an enlarged detail perspective view of one of the pedal-levers, &c.

Fig. 5 is a similar view of one of the pedals, showing the improved toe-clip. Fig. 6 is a detail elevation of the link connection with the intermediate crank of the crank-shaft. 55 Fig. 7 shows the manner of mounting the rear axle in the frame, also the chain adjustment. Fig. 8 is a detail section through the handle-bar and its stem, showing the manner of detaching the former. Fig. 9 is a detail 60 perspective view showing the manner of mounting and holding the brake-lever. Fig. 10 is a detail elevation of one of the hooks for connecting the foot-board to the machine-frame. 65

Similar numerals of reference designate corresponding parts in the several figures of the drawings.

The framework of the improved passenger-vehicle and carrier is constructed in the main 70 and wherever practicable of weldless or drawn steel tubing, such as is ordinarily employed in the manufacture of bicycles. The frame of the machine is substantially rectangular in plan, and consists of twin side frames 1, 75 extending longitudinally the entire length of the machine and of sufficient height to include between them and support the several parts of the machine. Each side frame comprises a lower and substantially horizontal 80 reach-bar 2 and an upper horizontal bar 3, the lower bar being extended in a straight line rearwardly to the point where the crank-shaft is located and then depressed or inclined downward in the direction of the rear 85 or main axle of the machine. The upper bar 3 of each side frame is bent downward at its advance end and joined to the corresponding end of the lower bar 2, and the rear end of the upper bar is also inclined downwardly 90 and rearwardly, so as to bring it into the proximal plane of the corresponding end of the lower bar 2, the rear ends of both bars being joined to a slotted bracket 4, in the slot 5 of which is received one end of the stationary main axle 6. The form of this bracket 95 4 is clearly illustrated in Fig. 7, in which it will be observed that an adjusting-screw 7 passes longitudinally through the central or web portion 8 of the bracket and bears at its 100 rear end against the axle 6. The object of this construction is to provide for tightening

or taking up slack in the drive-chain 9, which extends around and is driven by the main driving-sprocket 10 on the crank-shaft. After the axle 6 has been adjusted to the proper point it is clamped securely by means of jam-nuts 11.

12 designates a series of inclined tubular braces extending between and rigidly connecting the bars 2 and 3 of the side frames, 10 said braces being reversely inclined or arranged in zigzag order, as shown, whereby each side frame is effectively braced and strengthened.

The twin side frames 1 are spaced any suitable distance apart and are connected rigidly 15 at numerous points by means of tubular cross-bars. Two of such bars 13, arranged a slight distance apart, connect the advance ends of the lower bars 2 of the side frame, and another bar 13^a connects the same side bar 2 in close proximity to the rear axle 6. The bars 2 are also rigidly connected at intermediate 20 points by cross-bars 14 and 15, arranged, respectively, in front and in rear of the crank-shaft. Another cross-bar 16 connects the upper longitudinal bars 3 near the center of the machine, while still another cross-bar 17 connects the rearwardly-declining rear ends of the bars 3 at such point as to form a convenient 25 horizontal support for the passengers' seat, as will hereinafter appear.

18 designates the head-tube, in which the stem 19 of the front steering-fork 20 is revolvably mounted. This fork is of the usual 30 pattern and carries the steering-wheel 21 at the front of the machine. The lower end of the head-tube 18 is united rigidly to and between the cross-bars 13, above referred to, and is braced as to its upper end by means 35 of a lateral bar 22, which extends therefrom and connects rigidly to one of the side frames 1. The head-tube is further braced by means of a tubular bar 23, which extends rearwardly and connects with the seat-post tube, 40 (indicated at 24,) at or near the upper end of the latter. A supplemental inclined brace 25 is also interposed between the brace 23 and upper end of the head-tube, being rigidly connected to both. The seat-post tube 45 24 is supported at its lower end in a bracket or offset 26, connected centrally to and projecting forwardly from the cross-bar 14, above described. At its upper end the seat-post tube 24 carries a binding-collar 27, by means 50 of which the seat-post 28 may be securely clamped in rigid relation to the machine-frame and adjusted to the required height to accommodate the particular rider who is to operate the machine. The seat-post is provided 55 with the usual horizontal extension 29, which provides for the longitudinal adjustment of the operator's saddle 30, which may be of any ordinary description. The tubular fork-stem 19 is also provided at its upper end 60 65 with a binding-collar 31, which provides for the adjustment and removal of the handle-bar stem 32. By referring to Fig. 8 it will

be seen that the upper end of the stem 32 is reduced and squared, as shown at 33, thus forming a shoulder 34, upon which the handle-bar 35 may rest.

The central portion of the handle-bar is made solid in cross-section and provided with a squared vertical aperture of a size adapted to fit snugly over the squared upper end of the stem 32, and in order to hold the handle-bar in place when so applied recesses 36 are formed in opposite sides of the squared end 33, and in such recesses are located and permanently secured spring-catches 37. The 80 catches 37 have their upper ends reversely beveled, so that when the handle-bar is pressed downward said catches will be pressed inward or toward each other. Upon the handle-bar coming in contact with the shoulder 85 34 the catches 37 automatically spring apart and the shoulders of said catches engage above said bar, thus locking the same rigidly to the stem. When it is desired to remove the handle-bar, it may be quickly done by 90 compressing the catches 37 between the fingers until the shoulders of said catches will pass through the squared aperture of the handle-bar. The handle-bar is now free to be removed and may be carried upon the person 95 of the operator while the machine is left standing, thus materially obviating the liability of the machine being stolen.

When the handle-bar is removed, it is unnecessary to turn the steering-wheel to admit 100 the operator between the side portions of the frame, and this is an important advantage, as it is liable to injure the tire of the steering-wheel when turned to any appreciable extent, owing to the weight of the load that may 105 be carried upon the machine. It will be noted also that the lateral brace 22 is omitted upon one side of the head-tube 18, so as to allow the operator to pass between the head-tube and one of the side frames.

38 indicates a covering of leather, rubber, or other suitable material which passes around the front cross-bars 13 and extends upon each side of the head-tube 18, constituting foot-rests upon which the rider may rest his feet 115 while coasting or when standing still, thus preventing injury to the enamel or other finish of the machine-frame.

39 is a lamp-bracket attached, preferably, to the fork-stem or head-tube, as may be preferred.

The driving mechanism comprises, essentially, a transversely-disposed horizontal crank-shaft 40, of approximately half the width of the machine-frame. This crank-shaft 125 is mounted at or near its inner end in a crank-hanger 41, similar to that employed in the ordinary safety-bicycle, and supported in rigid relation to the machine-frame by means of a forward arm 42, extending to and connecting 130 rigidly with the cross-bar 14, and also connected to the cross-bar 15, above described, by means of one or more rearward arms 43. The crank-shaft 40 is provided at its inner

end with a terminal crank 44 upon one side of the hanger 41, and upon the other side of the hanger with a crank 45, and the shaft is mounted adjacent to its outer end in a bearing 46, attached to the lower horizontal bar 2 of the machine-frame by means of downwardly-converging short arms 47. The arms or bars, which are formed, preferably, of steel tubing, not only form a convenient support for the bearing 46, but also serve to brace or truss the side-frame at the point where the greatest bend occurs in the bar 2. The crank-shaft 40 has mounted fast upon its outer end the main driving sprocket-wheel 10, above referred to, and from which the chain extends to the rear axle for communicating the motion thereto.

48 designates a pair of pedal-levers, which are provided at their rear ends with eye-bearings or straps which embrace the rear cross-bar 14 of the frame construction upon each side of a tubular upright 49, rigidly connecting said cross-bar 14 with the bar 17, hereinbefore referred to. This prevents any springing of the bar 14 and provides a steady bearing for the rear ends of the pedal-levers.

Each of the levers 48 is provided at a suitable point intermediate its ends with a vertical longitudinal slot 50, through which 20 passes and in which oscillates a link or connecting-rod 51. The lower end of the link 51, below the lever 48, is received pivotally between a pair of V-shaped brackets 52, secured to the underside of the lever and spaced 25 apart a distance equal to the thickness of the lower end of the link, a through pin or pivot 53 being passed through the brackets and link and constituting the fulcrum between said parts. One of the links 51 is formed at 30 its upper end with an eye-bearing 54, in which is received the extremity of the terminal crank 44 of the crank-shaft 40, while the other link is provided at its upper end with a divided eye-bearing 55, by which it is adapted 35 to be brought into engagement with the crank 45, a strap 56 being employed for connecting the two parts of the bearing 55, with the aid of a retaining-bolt 57.

The pedals 58, located at the outer advance 40 ends of the pedal-levers, comprise each a base portion 59, either of metal or rubber or a combination of both, and adapted to receive the ball of the foot. The base of the pedal is pivotally mounted at the front end of its 45 respective pedal-lever by means of a pedal-pin 60 and has connected therewith a novel form of toe-clip. This toe-clip comprises a U-shaped portion 61, which attaches adjustably to the front edge of the pedal, from which 50 it extends forward a slight distance, after which it is recurved and extended backward, so as to reach approximately to the instep of the foot, at which point the said toe-clip is bifurcated or forked, as shown, the arms 62 55 of said fork being curved, so as to embrace and receive between them the foot of the op-

erator, and connected adjustably at or near their lower extremities to the rear edge of the pedal, as shown in Fig. 5. This construction of toe-clip enables the operator to 70 apply considerable additional power by pulling upward with one foot simultaneously with the pressing downward of the other foot. This assists materially in driving the vehicle upgrade or in starting the vehicle when heavily loaded or in the event of the roadway 75 being rough or heavy and sticky.

The pedal-levers 48 may of course be constructed of any suitable material; but it is preferred to employ four separate pieces or 80 thicknesses of hard wood, such as white oak, and rivet the same firmly together, in such manner, however, as to prevent the grain of the wood of the different pieces running all the same way. This affords a very desirable 85 and rigid pedal-lever and avoids the possible bending and consequent lost motion incident to the use of light-metal levers. By the construction described it will be observed that the bearing at the rear end of each pedal-lever, and the pedal at the forward end thereof, and the link 51 intermediate the ends 90 of the lever, and the connections of said link to the lever and crank-shaft are all located in exact longitudinal alinement. This results in obviating all side draft and the consequent additional friction which would result from such side draft and require additional power to drive the machine. Under 95 this arrangement each lever 48 is perfectly 100 balanced and there is no tendency for the same to tilt to one side or the other.

63 designates a canopy or top, preferably rectangular in form, which is adapted to be superposed above the heads of the operator 105 and passengers. The standard 64 of this canopy enters and is adjustably mounted in a vertical tubular post 65, attached rigidly at its lower end to and supported upon the crank-hanger 41 and at its upper end attached to 110 the horizontal cross-bar 16. The post 65 is also provided at its upper extremity with a binding-collar 66, by which the standard 64 may be adjusted and held.

The passenger's seat (indicated at 67) is 115 formed with a back 68, and both the seat and back are upholstered in any desired manner. Along the upper edge of the back 68 are arranged spring-hooks 69, secured permanently thereto and constructed in such manner that 120 their extremities are adapted to engage over the cross-bar 16 for supporting the back and the rear end of the seat in proper position. The forward edge of the seat rests upon and receives its support from the horizontal cross-bar 17, before referred to. For the convenience of the passengers a foot board or rest 70 is provided, the same having at its opposite rear corners attached hooks 72, which engage over the stationary axle 6. The foot-board is supported at its rear outer edge by 130 means of inclined rods 71, which extend from

the opposite rear corners of said foot-board upward to the bar 17, over which their ends are hooked.

72^a designates a textile apron or curtain, which extends transversely of the machine-frame and from the front edge of the seat to the inner end of the foot-rest for the purpose of protecting the clothes of the passengers from becoming soiled or entangled with the driving mechanism.

Upon one side of the machine, preferably the right-hand side, is mounted a brake-lever 73, having at its lower end a brake-shoe 74, resting normally in proximal relation to the rear carrying-wheel upon that side of the machine. The lever 73 is fulcrumed intermediate its ends upon a lateral stud upon the outside of one of the lower frame-bars 2 and is adapted to be engaged at its upper end by 20 rack-teeth on the bar 3 of the frame. The operator, sitting in the saddle 30, may readily grasp this brake-lever and by thrusting the same forward force the shoe thereof into engagement with the supporting-wheel. The 25 lever may be engaged with the teeth of the rack-frame for the purpose of holding the brake-shoe set, if desired. A bail-shaped frame 75, attached to the bar 3, defines the limit in which the upper end of the brake-lever moves, and a spring 75^a, carried by the 30 brake-lever, bears against the frame 75 and holds the brake-lever in engagement with the ratchet-teeth and prevents rattling of the lever.

By reason of the particular construction of the seat for the passengers and also the foot-rest 70 and the manner in which it is supported and connected to the machine-frame it will be seen that these parts may be readily 40 and quickly disconnected and removed from the machine, as also the canopy 63, with its standard. This allows a suitable cabinet or body 76 to be substituted for the passenger-seat, the same being supported in the main 45 upon the horizontal cross-bar 17 and connected to the frame construction at other points by hooks, as shown, or in any convenient manner. The use and application of the cabinet or body 76 is illustrated in Fig. 2, and 50 under this arrangement an excellent carrier is obtained, which may be utilized to the greatest advantage by wholesalers and retailers in the delivery of small packages.

One of the rear carrying-wheels 77 has attached to the inner end of its hub the small sprocket 78, around which runs the chain 9 from the main driving-sprocket 10, hereinbefore described. This is the preferred arrangement, as it will enable both of the rear carrying-wheels to turn independently and travel 60 at different speeds in swinging a corner.

From the foregoing description it will be seen that the passengers' seat is at the rear end of the vehicle and that it faces rearwardly, 65 while the operator's seat enables him to occupy a position at the front of the machine and to face in the direction in which travel-

ing. This greatly economizes space and renders the machine extremely compact and, as a result, lighter and stronger, as well as 70 cheaper in manufacture. Besides this the weight of the passengers or load is distributed proportionately, the excess of weight being thrown upon and carried by the rear wheels. It will also be seen that under the present 75 construction the pedal-levers are located beneath the vehicle-body and hang pendent from the crank-shaft, so that the links interposed between the levers and crank-shaft have a pulling instead of a pushing action. 80 The construction of the pedal-levers also enables the use of much longer connecting-links, and thus adds greatly to the smoothness and easy running of the driving mechanism. Finally, it will be noted as one important ad- 85 vantage of the present construction that the machine is quickly convertible from a carrier into a passenger vehicle, and vice versa, thus adding greatly to the desirability of such a 90 conveyance.

Changes in the form, proportion, and minor details of construction may be resorted to without departing from the spirit or sacrificing any of the advantages of this invention.

Having thus described the invention, what 95 is claimed as new is—

1. In a foot-propelled vehicle, the framework comprising a pair of twin parallel side frames having upper and lower bars extending the entire length of the vehicle and joined together at their front and rear terminals, a plurality of cross-bars connecting the side frames, and an upright front head-tube arising from the foremost cross-bars and having a brace connection with the front end of one 105 side frame, thereby providing the framework at one side of the head-tube with an open front space for the free passage of the operator, a foot-rest covering embracing the foremost cross-bars at the base of the head-tube, 110 a centrally-disposed crank-hanger having oppositely-extended arms joined respectively to two intermediate cross-bars, a seat-post extended upward from one of said intermediate cross-bars, and suitable driving mech- 115 anism having a crank-shaft journaled in the crank-hanger, substantially as set forth.

2. In a foot-propelled vehicle, the combination with a pedal, of a toe-clip adjustably secured to the front of said pedal and curved 120 to embrace the front portion of the foot and extended backward in proximal relation to the instep, the said clip being forked at the instep to embrace the foot and having the fork ends connected to the pedal, substan- 125 tially as described.

3. In a foot-propelled vehicle, the combination with a pedal, of a toe-clip shaped to embrace the front portion of the foot and provided adjacent to the instep with a fork the 130 arms of which extend downwardly so as to embrace the foot and are connected adjustably to the pedal, substantially as and for the purpose specified.

4. A toe-clip having its body portion bent so as to embrace the toe and provided at the front with a depending perforated extension for attachment to a pedal, said clip being further provided adjacent to the instep with a fork, the arms of which are bent downward and made divergent so as to extend upon opposite sides of the foot, said arms being also perforated for attachment to a pedal, substantially as described.

5. The combination with a handle-barstem having its upper end squared and provided at opposite sides with tapering recesses, and opposing spring-catches permanently secured to said stem and adapted to be deflected into said recesses, of a handle-bar provided at its center with a squared aperture adapting the handle-bar to be removably fitted upon the stem, the catches being extended sufficiently to pass through the aperture in the handle-

bar and to engage the top of the latter, substantially as described.

6. The combination with a handle-bar having an irregular aperture therein, of a stem having its end formed to fit said aperture 25 and also provided with recesses in opposite sides, and a pair of spring-catches carried by the stem and adapted to recede into said recesses, the said catches being adapted to automatically engage the handle-bar and lock 30 the same to the stem, substantially as described.

In testimony that I claim the foregoing as my own I have hereto affixed my signature in the presence of two witnesses.

GEORGE G. J. MILLAR.
